UNITED STATES PATENT OFFICE.

RONALD ELISON CAMPBELL, OF COLUMBIA, SOUTH CAROLINA, ASSIGNOR TO CHARLES C. WILSON, OF COLUMBIA, SOUTH CAROLINA.

ATTACHMENT FOR SMOOTHING-IRONS.

1,376,512.

Specification of Letters Patent. Patented May 3, 1921.

Application filed March 25, 1920. Serial No. 368,577.

To all whom it may concern:

Be it known that I, RONALD ELISON CAMPBELL, a citizen of the United States, residing at Columbia, Richland county, 5 State of South Carolina, have invented certain new and useful Improvements in Attachments for Smoothing-Irons, of which the following is a specification.

The object of this invention is to provide 10 means adapted for use in conjunction with the ordinary household smoothing iron, whereby the latter is rendered more efficient when being used in the usual manner, and which enables the operator to convert the 15 same into an electrical iron, quickly and conveniently by the further addition of an electrical heating unit. Briefly stated, the invention consists in a heat retaining casing of a size and shape suitable for receiving 20 within its walls, the body portion of an ordinary hand smoothing iron, and which may receive in addition to the iron, an electrical heating unit which, when connected to a source of electrical power heats the iron 25 continuously and enables it to be used as an electrical iron as though built as one in the first instance. If desired the casing may be used with the iron alone, without the electrical heating unit, and in this case it serves 30 to protect the hand of the user against the heat radiating from the body of the iron, and, in general, to prevent waste of heat through radiation to the air.

One embodiment of the invention is illustrated in the accompanying drawings, in which,

Figure 1 is a longitudinal sectional view through the heat retaining casing showing in elevation a smoothing iron and electrical 40 heating unit therein;

Fig. 2 is a side elevation of the casing showing in dotted lines the iron within, with an electrical heating unit of different type from that illustrated in Fig. 1, and in 45 a different position relatively to the iron;

Fig. 3 is a section on line 3-3 of Fig. 1;

Fig. 4 is a top view of the casing, the iron and heating element being omitted;

Fig. 5 is a plan view of one form of electrical heating element, a portion of its top being broken away to show the heating coils;

Fig. 6 is a section on line 6-6 of Fig. 4; and

Fig. 7 is a plan view of a different form

of heating element from that shown in Fig. 5 and drawn to a smaller scale.

The casing 10 may be formed in any one of a number of different ways and may be of any one of a variety of materials, but 60 preferably it is pressed or stamped from sheet metal, whereby the advantages of cheapness, strength and lightness of construction are realized. The casing has an opening in its rear end through which the 65 iron 11 and either form of heating element 12 or 13 may be inserted or withdrawn, and this opening is normally closed by a door 14 pivoted at its lower edge to the rear edge of the bottom wall of the casing. A sliding 70 latch 15, clearly shown in Fig. 3, normally holds the door in closed position, the end of the latch extending when in locking position through an opening in the side wall of the casing.

The iron 10 has the usual handle 16 rigidly secured thereto and the casing is necessarily slotted, as at 17 to enable the iron to be freely insertible. To prevent the heat of the iron from escaping through the slot 80 by radiation, a narrow cover plate 18 is provided which fits between the uprights of the handle and is removably held in place by a spring 19 pivotally secured to the top of the casing. An asbestos lining 20 secured to the 85 inside of the wall of the casing, prevents radiation of the heat of the iron to the surrounding air. The bottom of the casing however, has no asbestos or other heat insulating covering, to hinder the transfer of 90 heat from the iron to the work.

The electrical heating devices adapted to be used with the casing above described are preferably flat, as illustrated, and conform to the shape of the iron. As, in some cases, 95 the heating unit is most advantageously placed beneath the iron and in other cases, above the iron depending largely upon the character of work to be done, two forms of such heating elements are provided. The 100 electrical unit 12, is adapted to be placed beneath the iron while the unit 13, which is provided with a slot to receive the uprights of the iron handle is suitable for use on the upper side of the iron. The units themselves may be of any desired specific construction, and the wall thickness and size and arrangement of coils designed in various ways, depending upon the character of 105 work to be done and the size of the iron. 110

Sockets 12', 12' and 13', 13' respectively are provided in the rear portion of the electrical devices 12 and 13 to receive the conducting plugs of an electrical connector, such as illustrated in Figs. 1 and 2 to connect the coils of the heating devices to a source of electric current. To prevent rattling due to movement of the iron or heating device within the casing, set screws 21, 21 are provided which extend downwardly through threaded openings in the top of the casing. These set screws are operable from without and their lower ends bear down on the iron or heating unit, whichever is uppermost to prevent movement, whenever they are tightened.

The casing may be used with or without the heating unit. If used with a smoothing iron alone, it serves chiefly as a heat retainer for the hot iron which it contains, preventing wastage of heat through radiation and protecting at the same time the hand of the user. When both casing and heating devices are used, the ordinary iron is converted into an electric iron at slight expense. In case the heating element becomes damaged it may be withdrawn for repairs or replacement and the iron and protective casing used together until the broken part has been repaired or a new heating element obtained. It is not necessary, when the heating element becomes damaged, to employ the services of an electrician, the unskilled iron user being able to insert a new heating unit obtained from the manufacturer whenever necessary. It is obvious that changes may be made in the arrangement and construction of the parts of the invention, and I do not, therefore, limit myself to the embodiment described and illustrated.

Having thus described the invention what is claimed as new and desired to be secured by Letters Patent is:

1. In a device of the class described, a casing openable to receive the body portion of a smoothing iron, the handle thereof extending without the casing and said casing

being closable, to inclose the iron, for the purpose set forth. 50

2. In a device of the class described, a casing openable to receive the body of a smoothing iron, said casing being closable to inclose the iron, for the purpose set forth. 55

3. In a device of the class described, a casing openable to receive the body of a smoothing iron, said casing being closable to incase the iron and being provided with an asbestos lining, for the purpose set forth. 60

4. In a device of the class described, in combination, a flat electrical heating element adapted to be attached to a smoothing iron and a casing openable to receive the iron and heating element and closable to incase them and hold them in fixed position. 65

5. In a device of the class described, a casing openable to receive the body portion of a smoothing iron having a handle, the casing being provided with a slot through which the handle of the iron may extend. 70

6. In a device of the class described, a casing openable to receive the body portion of a smoothing iron having a handle, the casing being provided with a slot through which the handle of the iron may extend, 75 and means for closing the slot after the iron has been inserted in the casing, to retain the heat therein.

7. In a device of the class described, a casing openable to receive the body portion 80 of a smoothing iron having a handle, the casing being provided with a slot through which the handle of the iron may extend, a removable and replaceable plate for closing the slot after the iron has been inserted and 85 means for retaining said plate in closing position, for the purpose set forth.

8. In a device of the class described, in combination, a casing openable to receive the body portion of a smoothing iron, and 90 closable to incase the iron, and an electrical heating element in said casing and located between the bottom of the iron and the bottom of the casing.

In testimony whereof I affix my signature. 95
RONALD ELISON CAMPBELL.
